UNITED STATES PATENT OFFICE

CHRISTIAN CHRISTIANSEN, OF LYNN, MASSACHUSETTS, ASSIGNOR TO ROTARY MACHINE COMPANY, OF LYNN, MASSACHUSETTS, A CORPORATION OF MASSACHUSETTS

MECHANICAL MOVEMENT

Application filed May 5, 1927. Serial No. 189,143.

My present invention relates to mechanical movements and more particularly for mechanisms for giving to a shaft or shafts driven from a constantly rotating source of power, a rotary movement, the speed of which can be controlled by the operator.

It is the aim of my invention to provide a simple device embodying means for accomplishing these results.

While not limited thereto the device embodying my invention is especially adapted for use in connection with small machines as, for example, certain types of shoe machines such as edge folders where rollers which do the folding rotate at greatly varying rates of speed. In operating such machines, it is necessary to proceed slowly around a sharp bend or turn in the work and to proceed rapidly along the straight or substantially straight portions and it will be understood that there will be a great loss of time on the part of the operator if the speed of the machine is not completely under his or her control so that it may be speeded up instantly when the straighter portions are reached, and slowed down to any desired degree when the more difficult portions are reached.

The device embodying my invention is simple and reliable and is positive in its action. It also has the advantage that the mechanism which controls the speed of the device also stops and starts it which greatly improves the usefulness of the machine.

While it is to be understood that the mechanism embodying my invention is applicable to many other types of machines, for the purpose of illustration, I have shown it as embodied in a machine for applying adhesive tape or stay to parts of boots and shoes.

Referring to the drawings:

Fig. 1 is a side elevation partly in section of a machine embodying my invention;

Fig. 2 is an end view of the rollers;

Fig. 3 is an end elevation of the machine as viewed from the right of Fig. 1;

Fig. 4 is a similar view showing the parts in a different position;

Fig. 5 is a section taken on line 5—5, of Fig. 3;

Fig. 6 is a detail view of the clutches and certain of the associated parts;

Fig. 7 is a detail view in perspective of certain of the parts shown in Figs. 3 and 4;

Figs. 8 and 9 are diagrams illustrating the operation of the machine.

In Fig. 1, at A there is shown a suitable frame or support for the working parts of the machine. B and B¹ are two work rolls which apply the tape to the boot or shoe being treated. The tape is designated C and the work is designated D in Fig. 2. The upper roll B¹ is carried by a shaft 11 and the lower roll by a shaft 12. The upper roll is mounted in a bracket 13 forming part of the frame of the machine. The lower roll is mounted in a movable arm 14, itself mounted on a rock shaft 15 controlled by a treadle 16, and the connection 17 by means of which the pressure of the roll B on the work may be regulated by the operator, or the roll separated to permit the insertion or removal of the work. These parts are incidental to the particular use to which my invention is to be put and, therefore, need not be described any further in detail. The shaft 12 on which the lower work roll B is mounted is connected to the shaft 18 by a propeller shaft 19 and universal joints 20 and 21 which permit the shaft 12 to be moved relatively to the shaft 18 without cramping or binding either part.

The shaft 18 is parallel to the shaft 11 and the mechanism is intended to give to each of the shafts a rotary motion in opposite directions as indicated by the arrows in Fig. 6. Secured to the shaft 11 is a pinion 22 meshing with a corresponding pinion 23 on the shaft 18. These pinions are such that if either pinion is turned it will cause the other pinion and consequently the other shaft to turn with it. Each of the gears 22 and 23 is provided with a hub *a* into which extends a hub *b* loose on the shaft and secured to an arm. The arm for the upper shaft is designated 24 and the arm for the lower shaft is designated 25. These arms are connected by a link or connecting member 27. The hub *b* carries the cam surfaces of a roll or Horton

clutch, the rollers being designated 26 in Fig. 6. The clutches on the two shafts 11 and 18 are arranged to operate in the reverse directions. Thus, when the upper arm 24 moves in a counterclockwise direction as indicated in Fig. 6, the upper clutch on the shaft 11 is engaged and the gear 22 is caused to turn in the same direction by the arm 24. On the contrary when the arm 25 moves in 10 a counterclockwise direction, the lower clutch on the shaft 18 is disengaged from the pinion 23. It will be understood, however, that since the pinions are in mesh with each other, the upper pinion will move whenever the 15 lower pinion moves and vice versa. The result of this construction is that movement of the connecting member 27 in either direction produces a rotary movement of both pinions in the same direction. Thus, upward movement of the connecting member 20 27 drives the pair of pinions through the upper clutch, while downward movement turns the pair of pinions in the same direction through the lower clutch.

25 The mechanism by means of which the link 27 and consequently the two arms 24 and 25 are moved will now be described. At 28 (see Figs. 3, 4 and 5) is shown a lever pivoted at 29 to the lower arm 25. This lever has a 30 laterally extended portion 30, which is slotted as shown at 31 to permit it to swing in a vertical plane about the pivot 29 without colliding with the lower shaft 18. At 32 is shown a driving shaft of the machine provided with a suitable belt pulley 33. The inner end of said driving shaft 32 is provided with an eccentric pin 4 which as shown in Fig. 1 is forked and straddles the end of the lever 28. The forked eccentric pin 4 is free 40 to rotate in the shaft 32 and, therefore, forms in effect a crank which moves the end of the lever 28 up and down as the shaft 32 revolves. At 35 (see also Fig. 7) is shown a button slidably mounted upon the lever 28 and pivoted at 6 to the arm 37, the upper 45 end of which surrounds the upper shaft 11. The arm 37 may, therefore, be swung about the shaft 11 thereby causing the button 35 to travel lengthwise of the lever 28. The button being free to oscillate about the pivot 6, and to slide lengthwise of the lever 28 forms a movable fulcrum for the said lever. The movement of the button toward the right as shown in Figs. 3 and 5 is limited by a 50 stop 38 on the lever arm 28 and when the button is in contact with this stop the axis of the pivot 6 coincides with the axis of the pivot 29 by which the lever arm 28 is connected to the clutch arm 25. It will, therefore, be seen that when the button 35 is in this position (see particularly Fig. 3) it will cease to act as a fulcrum for the lever 28 and consequently the arm 25 will not be oscillated by said lever. On the contrary, when the 55 button 35 is moved to the left as shown in

Figs. 4 and 7 the lever 28 swings about the pivot 6 of the button as a fulcrum, this movement being caused by the crank pin 4 as already described and consequently the right hand end of the lever 28 moves the right hand end of the arm 25 up and down an amount determined by the position of the button 35 on the arm 28. It will be understood that the farther the button 35 is moved to the left the greater will be the stroke of the clutch arm 25 since the length of the portion of the lever 28 lying at the right of the fulcrum 6 will be proportionally increased thereby, and the portion of the lever which lies between the fulcrum 6 and the crank pin 4 correspondingly shortened. 75

To swing the arm 37 about the shaft 11 to control the position of the movable fulcrum 6 there is provided a bell crank lever 39 pivoted at 40 to the frame of the machine. The upper arm *d* of this bell crank lever contacts with the lower end of the movable fulcrum arm 37 and the other arm *e* of the bell crank is connected to a treadle 40 by a connection 41. The movable fulcrum arm 37 is normally held against the stop 38 by means of a spring 42. 90

The operation of these parts will be clearly understood by reference to the diagrams forming Figs. 8 and 9 of the drawings. In these diagrams the parts are indicated by the same numbers as in the preceding figures but the several members are indicated by single lines and the pivots by small circles. From these it will be seen that when the parts are in the position shown in Fig. 8 the fulcrum arm 37 is at the extreme right and the axis of the button 35 coincides with the axis of the pivot 29 by means of which the lever arm 28 is connected to the lower clutch arm 25 and rotation of the crank 4 will impart an idle motion to the lever 28 but this motion will not be transmitted to the lower clutch arm 25. At this time, therefore, the working parts of the machine will stand still. When the operator 100 desires to cause the work rolls B and B¹ to rotate he will depress the treadle 40. This will swing the movable fulcrum arm 37 to the left moving the button 35 away from the stop 38. As the button moves to the left, the length 105 of the part of the lever arm on the right thereof increases. Since the lever 28 is now fulcrumed about the pivot 6 as its left hand end is moved up and down, the right hand end will be given a reciprocal movement in the opposite direction, the amount of said movement being proportioned to the relative length of the two lever arms. Consequently 110 the amount of movement imparted to the shafts 11 and 18 will be proportioned to the position of the movable fulcrum 6 and the peripheral speed of the rollers increased as the movable fulcrum is shifted toward the left as shown in Figs. 3, 4, 8 and 9. When it is desired to stop the machine it is only necessary 115 to move the button 35 to the right so as to bring it into contact with the stop 38. 120

sary to let up on the treadle 40 and permit the spring 42 to push the movable fulcrum arm 37 to the right against the stop 38.

Since the arc of movement imparted to the clutch lever arms at each rotation of the main shaft is very small and since the main shaft is ordinarily designed to run at relatively high speeds it is found in practice that the rotation of the two shafts is so steady that the intermittent movement is not perceptible in the operation of the machine. I find in practice that the mechanism described can be run at high speeds but is at all times under perfect control of the operator. It imparts to the two shafts a positive motion and since the drive is not through any friction clutch the machine is more reliable and more satisfactory in operation than would otherwise be the case.

It will be understood that the mechanical motion herein described is applicable not only to motions having two parallel shafts but also to machines having only one shaft. This will be readily understood if it be assumed that the shaft 18 is cut off between the gear 23 and the universal joint 21. In this case the shaft 11 will be driven by the mechanical motion exactly as before. Under these circumstances the mechanical motion is identical in construction and mode of operation but is employed to turn one shaft instead of two.

What I claim is:

1. The combination of a pair of pinions intermeshing to rotate in opposite directions, oppositely acting roll clutches for rotating said pinions, a pair of connected members for operating said clutches, a constantly rotating shaft, a lever device oscillated constantly from said shaft and connected to said members to oscillate the same in unison and thereby operate the clutches in unison, said lever device comprising a lever and a fulcrum movable independently on said lever for varying the oscillating stroke of said members and thereby the speed of rotation of the pinions, a spring for moving said fulcrum in one direction and a lever for moving the fulcrum in the opposite direction.

2. The combination of a shaft, a pinion on said shaft, a second pinion intermeshing therewith, oppositely acting one-way roll clutches for driving both of said pinions in opposite directions, common actuating means for both of said clutches including an oscillating lever device connected to said clutches, said lever device comprising a lever and a movable fulcrum to vary the stroke of said lever, spring means for shifting said fulcrum in one direction, and a treadle operated lever for shifting the fulcrum in the opposite direction.

In testimony whereof I affix my signature.
CHRISTIAN CHRISTIANSEN.
